UNITED STATES PATENT OFFICE

FREDERICK L. G. STRAUBEL, OF GREEN BAY, WISCONSIN

EXPANDING LETTER FILE

Application filed September 11, 1930. Serial No. 481,122.

My invention relates to the class of letter files which will permit the contents of the file to be expanded, so that any letters or other papers in the file can be inspected without taking any part of the file contents out of the file. Arrangements for this purpose have heretofore been afforded in file cabinets by equipping the cabinet drawers with forwardly tilttable fronts and rearwardly tilttable followers connected to each other for conjoint movement. However, the providing of such provisions on a slideable drawer, constructed separately from the cabinet itself, adds to the total cost of the cabinet and the relative increase in cost is proportionately rather high for a single deck file cabinet.

My present invention aims to provide a single deck file which will afford the desired expanding of the contents without requiring either a sliding drawer or a follower separate from the back of the file, which will permit ready access to the file contents when the cover of the cabinet is swung out of its normal closure position, and in which the opening and closing of the cover automatically will respectively expand and compact the file contents.

Moreover, my invention aims to provide an expanding file of these characteristics which can cheaply be constructed of sheet metal, which will be rigid both in its closed and in its opened disposition, which will employ the back of the cabinet as a tilttable follower, and in which simple provisions will afford the operative connections whereby an opening movement of the lid or cover of the file will tilt the front and back of the file away from each other.

Still further and also more detailed objects will appear from the following specification and from the accompanying drawings, in which

Fig. 1 is a perspective view of an expanding letter file cabinet embodying my invention, showing this with the lid or cover in its opened position, and with a portion of the tilttable file front broken away.

Fig. 2 is a vertical and longitudinal section through the lower portion of the same file, taken along the line 2—2 of Fig. 1.

Fig. 3 is a vertical section similar to Fig. 2, but taken through the complete letter file when this is closed.

Fig. 4 is an enlarged and fragmentary horizontal section taken along the line 4—4 of Fig. 3.

Fig. 5 is an enlarged and fragmentary vertical section, taken transversely of the file along the line 5—5 of Fig. 3.

In the illustrated embodiment, my expanding letter file has a box-like hollow base including a bottom 1, a base top 2, and front and rear base walls 3 and 4. The sides 5 and 6 of this hollow base extend upwardly beyond the base top 2 for a distance greater than the height of the papers which are to be filed, and these ends respectively form the two upright and stationary sides of the file.

The front 7 and the back 8 of the file are pivoted at their lower ends respectively to the upper edge portions of the front and the rear base walls 3 and 4, upon horizontal hinge axles 9, and the said front and rear are both extended above the base top 2 to the same height as the stationary file sides 5 and 6.

Stiffening webs 10 and 11 extend rearwardly from the two side edges of the front 7, these webs being respectively adjacent to the inner faces of the sides 5 and 6 when the file is closed as in Figs. 3 and 4, and the back 8 has similarly disposed but forwardly directed stiffening webs 12 and 13 respectively at its opposite side edges.

To connect the front operatively with the back, I equip these two tilttable file parts adjacent to each side of the file with relatively overlapping wings and provide a suitable connection between at least two of these overlapping wings. As here illustrated, the back 8 has two quadrant-shaped wings 14 and 15 extending forwardly from it and rigidly connected to it, as by welding these wings respectively to the webs 13 and 12. The front 7 is similarly equipped with wings 16 and 17 which extend rearwardly and desirably are welded respectively to the webs 11 and 10. Each of these quadrant-shaped wings is of greater length than half of the distance between the front and the back of the file, so

that the two wings at the same side of the file continuously overlap, as shown in Figs. 2 and 3. When thus equipped with wings and webs, the tilttable front member comprises the front 7, webs 10 and 11, and wings 16 and 17; and the tilttable back member comprises the back 8, webs 12 and 13, and wings 14 and 15.

One of the wings at one side of the file (such as the rear wing 14) is provided with a slot 18 which extends obliquely downward toward the wing overlapped by it when the file is closed, and the overlapped wing 16 has a pin 19 extending into and slidable in this slot. When the back 8 is swung rearwardly (or from the upright position of Fig. 3 to the tilted position of Figs. 1 and 2), the web 14 which is equipped with the slot 18 swings with it, and the swinging movement raises the slot, thereby causing the lower edge of the slot to lift the pin 19, so as to rock the front 7 forwardly until the pin 19 engages the forward end of the slot to limit the separational swinging movement of the file front 25 and back.

Likewise, a swinging movement of the back from its tilted position of Fig. 2 towards an upright position will cause the upper edge of the slot 18 to press downward on the pin 19, thereby swinging the front also to its upright position, so that the front and the back always move conjointly towards and away from their upright positions. In practice I preferably provide such slot and pin provisions as connections between the overlapping wings at each side of the file.

As a closure for the top of the filing space (which is laterally bounded by the four file walls—namely the front 7, back 8, and the sides 5 and 6) I provide a cover, desirably in the form of an inverted rectangular box which includes upright walls 20 which have more widely spread lower end portions 30 spaced so as to depend outside the said four file walls when the file is closed, and which cover also includes a cover top 21.

This cover has each of its side walls 20 A connected to the back member by a rear link 22 which extends obliquely forward upwardly when the file is closed as in Fig. 3, this link being desirably pivoted at its lower end to the adjacent web (12 or 13) of the back member.

Each of the cover sides 20 A also is connected to the adjacent file side (5 or 6) by a generally more forward link 23 which is longer than the adjacent rear link 22. This longer link is desirably pivoted at its lower end to the adjacent file side by a pivot pin 24 disposed higher than the pivot pin 25 which connects the lower end of the adjacent link 22 to one stiffening web on the file back; and the long link has its upper end pivoted to a cover side by a pivot pin 26 disposed considerably further forward than the pivot

pin 27 on which a rear link 22 is pivoted to the same cover side.

Owing to this disposition of the pivots and to the relative length of the links, a lifting of the cover by raising a handle 28 will lift the front portion of the cover more rapidly than the rear portion, and the swinging movement of the links due to the lifting will move the cover bodily rearward during its raising. During this raising of the cover, the connection of each of the longer links 23 to the cover describes an arc 29 (as shown in dotted lines in Fig. 1), thus moving the front portion of the cover both upwardly and rearwardly. Meanwhile, the rigid spacing of the pivot pins 26 and 27 compels the upper ends of the rear links to move rearwardly to a corresponding extent, in doing which these rear links engage the back 8 of the file and tilt this back rearwardly.

This outward tilting of the back 8, through the slot and pin connection between the quadrant-shaped wings, simultaneously tilts the front 7 forwardly until the separating tilting movement is halted by the engagement of the pin 19 with the end of the adjacent slot 18, thereby disposing the file parts as shown in Fig. 1. With the parts proportioned as here illustrated, namely so that the upper end of each forward link swings further rearward than its lower end when the file is being opened, gravity causes the cover to press the rear links 22 firmly against the back when the file is opened as in Fig. 1, and holds the cover in a position in which the user has ready access to the expanded file.

With the parts proportioned as here illustrated, each rear link extends across the adjacent longer link when the file is closed, this being permitted by an inward offsetting of the medial portion of the rear link, as shown in Fig. 5. The overlapping portions of the two interlocked wings at either side of the file must also swing alongside each other, for which purpose the tip portion 16 A of the front wing in Figs. 3 and 4 is here shown as offset outwardly from the main portion 16, while the rear wing 14 at the same side of the file is flat.

Each of these wings (14 to 17 inclusive) also preferably has its lower edge radial of the pivot axis of the file wall to which it is attached, and disposed for seating on the base top 2 when the file is closed, so as to increase the rigidity of my file when closed.

In practice, the webs which extend rearwardly from the front and forwardly from the back also prevent lower corner portions of the file contents from sliding or projecting out of the file when this is opened.

However, while I have heretofore described my invention in an embodiment including numerous desirable details of construction and arrangement, I do not wish to be limited in these respects, since many

changes might be made without departing either from the spirit of my invention or from the appended claims. Nor do I wish to be limited as to the nature and size of the 5 contents for which my expanding file may be employed, although I have found this particularly suitable as a desk companion designed for filing documents of ordinary letter size.

10 I claim as my invention:

1. An expanding file including a base member; a front and a back respectively hingedly connected at their lower ends to spaced portions of the base member; two upright sides 15 rigidly connected to the base member and normally cooperating with the front and back to form a container; and means operatively connecting the front and back for causing a swinging of one thereof in one direction to 20 swing the other thereof in the opposite direction, said means comprising a rearwardly directed wing rigidly connected to the front, a forwardly directed wing fast on the back, and partly overlapping the aforesaid wing, 25 and connections between the two wings whereby a movement of one wing moves the other wing in the opposite direction.

2. An expanding file including a base member; a front and a back respectively hingedly 30 connected at their lower ends to spaced portions of the base member; two upright sides rigidly connected to the base member and normally cooperating with the front and back to form a container; and means operatively connecting the front and back for causing a 35 swinging of one thereof in one direction to swing the other thereof in the opposite direction, said means comprising a rearwardly directed wing rigidly connected to the front, a 40 forwardly directed wing fast on the back and partly overlapping the aforesaid wing, and connections between the two wings whereby a movement of one wing moves the other wing in the opposite direction, and means 45 associated with the said connections for limiting the separational movement of the two wings.

3. An expanding file including a base member; a front and a back respectively hingedly 50 connected at their lower ends to spaced portions of the base member; two upright sides rigidly connected to the base member and normally cooperating with the front and back to form a container; and means operatively connecting the front and back for causing a 55 swinging of one thereof in one direction to swing the other thereof in the opposite direction, said means comprising a rearwardly directed wing rigidly connected to the front, a 60 forwardly directed wing fast on the back and partly overlapping the aforesaid wing, and connections between the two wings whereby a movement of one wing moves the other wing in the opposite direction; the said connections 65 comprising a slot formed in the rear wing

and extending forwardly downward, and a pin fast on the forward wing and slidably engaged by the slot.

4. An expanding file including a base member; a front and a back respectively hingedly 70 connected at their lower ends to spaced portions of the base member; two upright sides rigidly connected to the base member and normally cooperating with the front and back to form a container; and means operatively connecting the front and back for causing a swinging of one thereof in one direction to swing the other thereof in the opposite direction, said means comprising a rearwardly directed wing rigidly connected to the front, a 75 forwardly directed wing fast on the back and partly overlapping the aforesaid wing, and connections between the two wings whereby a movement of one wing moves the other wing in the opposite direction; the said connections comprising a slot formed in the rear wing and extending forwardly downward, and a projection fast on the forward wing and slidably engaged by the slot, the slot being 80 of such length that an end thereof will engage the projection to limit the relative movement of the two wings in one direction.

5. An expanding file including a base member; a front and a back respectively hingedly 85 connected at their lower ends to spaced portions of the base member; two upright sides rigidly connected to the base member and normally cooperating with the front and back to form a container; and means operatively connecting the front and back for causing a 90 swinging of one thereof in one direction to swing the other thereof in the opposite direction, said means comprising a rearwardly directed wing rigidly connected to the front, a forwardly directed wing fast on the back 95 and partly overlapping the aforesaid wing, and connections between the two wings whereby a movement of one wing moves the other wing in the opposite direction; each wing having its lower edge disposed for engaging 100 the top of the base member when the said front and back are in upright positions.

6. An expanding file including a base; two stationary sides; a normally upright front; a normally upright back hinged at its lower end to the base; a cover normally supported by the two sides and overlying the space between the sides, front and back; and means connecting the cover to both sides and to the back, the said means being arranged for simultaneously tilting the back rearwardly when the forward portion of the cover is raised.

7. An expanding file including a base member; a front member and a back member respectively hinged at their lower ends to 115 spaced portions of the base member; two upright sides rigidly connected to the base member and normally cooperating with the front and back to form a container; means operatively connecting the front member and 120

125

back member for causing an outward swinging of one thereof to swing the other outwardly also; in combination with a movable cover; and means connecting the cover with both the back member and the two sides 5 whereby a raising of the cover swings both the front member and the back member outwardly and swings the cover to a position in which the center of gravity of the cover is disposed rearwardly of the rear edges of the 10 two sides.

8. An expanding file including a base member; a front member and a back member respectively hinged at their lower ends to the base member; two upright sides 15 rigidly connected to the base member; a cover overlying the space bordered by the said front member, back member and sides when the front member and back member 20 are also in upright positions; and two pairs of links connecting the cover respectively both with the back member and the said sides; the cover being of a cap-like formation including two cover sides to which the upper ends of all of the links are pivoted.

9. An expanding file comprising a stationary portion including two upright sides; a front, a back; hinges respectively connecting the lower end of the front and the lower end 30 of the back to the stationary portion on horizontal axes transverse of the sides; means operatively interposed between the front and the back whereby a swinging movement of either of the latter two members about the hinge associated with it will swing the other member in the opposite direction; a cover 35 normally supported by the two sides overlying the space between the front, back and sides; a pair of links respectively connecting the two sides with forward portions of the cover, and a second pair of links respectively connecting the back with more rearward portions of the cover; the links of the second pair being shorter than those of the first named 40 pair, thereby causing a raising of the cover to swing the back rearwardly and also to move the cover rearwardly into a position in which the cover only partially overhangs the back.

10. An expanding file as per claim 9, including means for limiting the separational movement of the front and back; the shorter links being disposed for engaging the back to limit their rearward swinging, thereby limiting the rearward swinging of the cover 55 by the two pairs of links.

11. An expanding file comprising a stationary portion including two upright sides; a front; a back; hinges respectively connecting the lower end of the front and the lower end 60 of the back to the stationary portion on horizontal axes transverse of the sides; means operatively interposed between the front and the back whereby a swinging movement of either of the latter two members about the hinge associated with it will swing the other

member in the opposite direction; the back having forwardly directed webs normally respectively adjacent to the inner faces of the two sides; a cover normally supported by the two sides and overlying the space between the front, back and sides; a pair of long links respectively connecting portions of the cover to the two sides; and a pair of shorter links respectively connecting more rearward portions of the cover with the said webs. 73

12. An expanding file as per claim 6, in which the sides have portions thereof disposed for engaging the cover to limit the return swinging movement of the cover, the cover being seated upon the said portions of the sides when the file is closed. 80

Signed at Green Bay, Wisconsin, September 8th, 1930.
